UNITED STATES PATENT OFFICE.

JOHN JUNKUNC, OF CHICAGO, ILLINOIS.

LOCK.

Application filed January 17, 1924. Serial No. 686,698.

This invention relates to locks, more particularly those of the type in which a curved bolt is slidably connected to a barrel and is held in locking position by mechanism within the barrel.

The principal objects of the invention are to improve, simplify and cheapen the construction of such locks.

Other and further important objects of this invention will be apparent from the disclosures in the drawings and accompanying specification.

The invention (in a preferred form) is illustrated in the drawings and hereinafter more fully described.

On the drawings:

Figure 1 is a side elevation of a lock constructed in accordance with the present invention.

Figure 2 is a central longitudinal section through the lock in closed position.

Figure 3 is a view similar to Figure 2 showing the lock in open position.

Figure 4 is a section on the line 4—4 of Figure 3.

Figure 5 is a section on the line 5—5 of Fig. 3.

Figure 6 is a side elevation of one of the parts.

As shown on the drawings:

The lock comprises a case hardened barrel or casing 10 having two parallel cylindrical recesses 11 and 12 for the reception of the ends 14 and 15 of the curved bolt 13. One of these ends 15 is formed with a portion 16 of reduced diameter to enable a threaded pin 17 to be inserted opposite such reduced part to prevent complete withdrawal of the bolt while allowing the latter to rotate when in its extended position. Extending outwardly from this reduced part 16 is a flattened portion 18 adapted to allow the bolt to be slid into locking position.

In the recess 12 is arranged a spring 19 adapted to move the bolt into unlocked position as soon as it is released.

The bolt is held in locked position by a pair of balls 20 adapted to enter recesses 21 in the ends of the bolt. These balls are held in engagement with these recesses by a reciprocable member 22, the end of which is formed with two arcuate recesses 23 to allow such end to pass between the balls as shown in Figure 2.

The member 22 is slidably arranged in a cylindrical recess 24. In this recess is

arranged a sleeve 25 held in position by a set screw 26. This set screw is inserted from the recess 11 so that it can only be reached when the lock is open. Within this sleeve 25 is the rotatable tumbler 27 having a slot 28 for the reception of a key.

Around the inner end of the tumbler is a sleeve 29 having projections 30 adapted to engage slots in the periphery of the member 22. These projections are flattened after the member 22 has been brought into engagement so as to form a T-head which securely holds the parts together.

The sleeve 29 is cut away longitudinally on opposite sides to receive projections 31 on the sleeve 25 so that while the sleeve 29 is free to reciprocate it cannot rotate within the barrel 10.

Between the tumbler 27 and the sleeve 29 is arranged a spring 32 which tends to force the latter, and the member 22 attached thereto, towards the balls 20. For moving the sleeve 29 in the opposite direction this sleeve is formed with oblique cam surfaces 33 adapted to be engaged by pins 34 on the tumbler 27 when the latter is rotated by its key. Shoulders on the sleeve 25 are provided to engage the pins 34 and thereby limit the range of movement of the tumbler.

To hold the balls more securely in locking position recesses 35 are provided at the end of the recess 24.

I am aware that numerous details of construction may be varied through a wide range without departing from the principles of this invention, and I therefore do not purpose limiting the patent granted otherwise than necessitated by the prior art.

I claim as my invention:

1. A lock comprising a barrel, a curved bolt slidably connected thereto having a recess therein, a ball within said barrel adapted to enter said recess when the bolt is in locking position, a member reciprocable within the barrel parallel to the bolt adapted to move behind the ball when the latter enters said recess to retain the ball in engagement with the bolt, and means for reciprocating said member.

2. A lock comprising a barrel, a curved bolt slidably connected thereto having a recess therein, a ball within said barrel adapted to enter said recess when the bolt is in locking position, a member reciprocable within the barrel parallel to the bolt adapted to move behind the ball when the latter

2
enters said recess to retain the ball in engagement with the bolt, a spring for moving said member in one direction and key operated means for moving it in the opposite direction.

3. A lock comprising a barrel having recesses therein adapted to receive the ends of a curved bolt, said ends having recesses therein, a pair of balls within said barrel and between said ends, adapted to enter the last mentioned recesses, a member reciprocable within the barrel parallel to the bolt adapted to separate said balls to retain the latter in engagement with the ends of the bolt and means for reciprocating said member.

4. A lock comprising a barrel having recesses therein adapted to receive the ends of a curved bolt, said ends having recesses therein, a pair of balls within said barrel and between said ends adapted to enter the last mentioned recesses, a member reciprocable within the barrel parallel to the bolt adapted to separate said balls to retain the latter in engagement with the ends of the bolt, a rotatable tumbler within said barrel,

a spring for moving said member in one direction, and a projection on the tumbler adapted to engage a cam surface on said member for moving the latter in the opposite direction.

5. A lock comprising a cylindrical barrel having a recess extending therein parallel to the flat sides of the barrel, a curved bolt, a pair of recesses parallel to the first recess entering the barrel from the opposite side and adapted to receive the ends of said curved bolt, a pair of balls adjacent the inner end of the first recess adapted to enter recesses in the ends of said curved bolt, a member reciprocable within the first recess to separate the balls to retain the latter in engagement with the ends of the bolt, a rotatable tumbler within said first recess, a spring for moving said member in one direction, and a projection on the tumbler adapted to engage a cam surface on said member for moving the latter in the opposite direction.

In testimony whereof I have hereunto subscribed my name.

JOHN JUNKUNC.
